SANITARY PAPER HOLDER

Thomas Charles Fowler, Mount Albert, Auckland,
New ZealandApplication May 26, 1934, Serial No. 727,822
In New Zealand June 2, 1933

3 Claims. (Cl. 242—55.2)

The invention relates to holders for rolls of sanitary or toilet paper in which the rolls are mounted so that sections of paper can be detached by tearing as required.

5 The object of the invention is to provide for the aforesaid purpose, an improved form of holder from which a roll of paper after having once been properly mounted and secured therein, cannot be removed except by the customary 10 method of tearing or detaching the paper one section or piece at a time, while each of the latter is of the same and a predetermined length.

According to the invention the improved holder 15 comprises a hollow flat-sided core pivoted between brackets or lugs, by means of removable pins normally retained in the core by locking means, access to which is prevented by a roll of paper placed on said core.

In order that the invention may be clearly 20 understood a holder or device constructed in accordance therewith will be described in conjunction with the accompanying drawing in which:—

Figure 1 is a view in perspective of a holder with a roll of paper thereon

25 Figure 2 a front view of the holder with the paper removed

Figure 3 a rear view of the core

Figure 4 a cross sectional view of the latter on the line 4—4

30 Figure 5 a view of one of the core pivot pins

Figure 6 a view of the locking spring and

Figure 7 an illustration of a blank from which a core can be formed.

In producing the holder in a form suitable for 35 use there is provided a back plate 1 from which extend a pair of spaced brackets or lugs 2, the back plate 1 being provided with holes or slots 3, through which it can be secured to a wall or other fixture by screws or other suitable fastenings, 40 while the brackets or lugs 2 contain holes 4 to enable a core 5 adapted to be inserted in a roll 12 of paper, to be pivotally mounted between them.

The core 5 is formed preferably from a piece 45 of sheet metal shaped as illustrated in Figure 7, with a slot 6 at the centre of one end and containing an opening 7 near its other end, said opening being disposed midway between the long edges of the piece of sheet metal.

The metal blank thus produced is utilized to 50 obtain a hollow flat sided core by first rolling the edge portions 8 at each side of the slot 6 and then doubling the blank on the line 9.

Just before bringing the rolled edge portions 55 8 right down onto the central portion of the metal blank, a wire spring 11 formed as shown

in Figure 6 is placed between the doubled portions so that the smaller end of the spring is located in the slot 6 between the rolled edge portions 8 with the upturned cross member 11a of said spring located between the inturned rolled edge of the blank and the line 10, so that upon the blank being doubled or bent on the last mentioned line and brought over the already inturned portion, the opening 7 will expose and give access to the smaller end of the spring 11 now housed 10 and held with its coils and outwardly flared legs, between the first inturned portion of the blank and the centre portion thereof said coils being clear of the rolled edge portions 8 as indicated by dotted lines in Figure 3.

15 The doubled or bent portions of the blank are, if need be, secured together by soldering or other means.

The core 5 is inserted in the centre of a roll 12 of paper and is pivotally mounted between the 20 brackets or lugs 2 by pins 13 provided with heads 13a and containing circular grooves 14 near their pointed ends, said pins 13 being passed through the holes 4 in the brackets or lugs 2 into the 25 rolled edge portions 8 of the core 5 until the side members of the small end of the spring 11 snap into the circular grooves 14 and lock said pins 13 against withdrawal, while the heads 13a on the latter prevent the brackets or lugs 2 from 30 being spread to allow the outer ends of the pins 13 to be disengaged therefrom.

By reason of the location of the rolled edge 35 portions 8 nearer to the top of the core 5 than to the bottom thereof, the greater portion of the weight of the core and the roll 12 thereon is below the pins 13, with the result that the core 5 normally hangs vertically with the free end of the roll of paper hanging from the front of the roll.

A stop 15 projecting from the lower edge of the 40 core 5 at one end thereof by engaging the lower and upper edges of the adjacent bracket or lug 2 limits turning movement of the core 5 and roll 12 in the brackets or lugs 2 to approximately three quarters of a circle.

In order to detach or tear off a section or piece 45 of paper from the roll 12, the free end of the latter hanging down the front of the device is gripped and pulled downwards, which action results in the roll and core turning between the brackets or lugs 2 until the stop 15 strikes the 50 lower edge of the adjacent bracket or lug, with the result that the paper gripped is detached or torn from the roll 12 along a line of perforations somewhere across the upper portion of the roll.

The core 5 and roll 12 then return to the former or normal position by gravity, while the new free edge of the paper drops down between the roll and the plate 1 to hang down the front of the device in readiness for the next operation.

As will be seen from the description and illustrations of the device, once a roll of paper has been properly mounted in the holder, the opening 7 which gives access to the spring 11 is covered and the latter cannot be got at to unlock the pins 13 so that they may be withdrawn until such time as the whole of the paper and the hollow cardboard or similar core usually supplied therewith have been removed, following which it is a simple matter to operate the spring 11 by applying pressure to the cross connecting member 11a for the purpose of disengaging the side members of the small end of said spring from the grooves 14 in the pins 13 and so permit the latter to be withdrawn and the core 5 removed to enable a fresh roll to be mounted and locked in the holder.

As the pins 13 are provided with heads 13a, the brackets or lugs 2 cannot be forced apart off the pins 13, so that there is no way of removing the roll from the holder, except by detaching or tearing off the paper section by section, and as the latter are each of a predetermined length according to the spacing of the perforations,

theft of rolls is prevented, and extravagant use of paper is discouraged.

What I do claim and desire to obtain by Letters Patent of the United States of America is:—

1. A holder for sanitary or toilet paper comprising a pair of spaced supporting brackets, a hollow flat-sided paper receiving core, a pair of headed pins grooved at their outer ends and slidably mounted in said brackets and housed within the core to pivotally mount the core eccentrically of the brackets, and locking means in the form of a spring member housed within the core and engaging the grooves in the pins to prevent accidental displacement of the pins and having a portion accessible when the core is empty to facilitate the removal of the spring member from engagement with the pins.

2. A holder as claimed in claim 1, wherein the core is formed from a rectangular blank of sheet metal provided with apertures which register with each other when the core is folded and which receive the projecting portion of the spring member.

3. A holder as claimed in claim 1, wherein a stop is fixed to one end of the core and is adapted to prevent complete rotation of the core in the brackets.

THOMAS CHARLES FOWLER.
